ELBOW OR KNEE PROTECTING PAD

Ethel M. Marvid, 5316-18 S. Hoover St.,
Los Angeles, Calif.

Filed Aug. 14, 1961, Ser. No. 66,341

Term of patent 14 years

(Cl. D3—26)

I claim:

The ornamental design for an elbow or knee protecting pad, as shown.
